(57) **CLAIM**

The ornamental design for a ruler, as shown and described.

DESCRIPTION

FIG. 1 is a perspective view of a ruler showing my new design;

FIG. 2 is a front elevational view thereof;

FIG. 3 is a rear elevational view thereof;

FIG. 4 is a top view with the bottom view being a mirror image thereof; and,

FIG. 5 is a right side elevational view with the left side being a mirror image thereof.

The front of the ruler is transparent so as to allow the opaque rear surface thereof bearing rulings to be viewed from the front.
